Primary Examiner — Austin Murphy(74) *Attorney, Agent, or Firm* — Kevin P. Crosby;
GrayRobinson, P.A.(57) **CLAIM**

The ornamental design for arched hole card reader, as shown and described.

DESCRIPTION

FIG. 1 is a left front perspective view of a second embodiment of the design.

FIG. 2 is a top plan view thereof.

FIG. 3 is a right side elevational view thereof.

FIG. 4 is a front elevational view thereof.

FIG. 5 is a bottom plan view thereof.

FIG. 6 is a rear elevational view thereof.

FIG. 7 is a left elevational view thereof.

FIG. 8 is a right front perspective view thereof.

FIG. 9 is a left rear perspective view thereof; and,

FIG. 10 is a right rear perspective view thereof.

The broken lines shown in the drawings represent portions of the arched hole card reader that form no part of the claimed design.
